(57) **CLAIM**

The ornamental design for a pair of rear fenders, as shown and described.

DESCRIPTION

FIG. 1 is a perspective view of a one of a pair of rear fenders shown with a vehicle in broken line format, the other one of the pair of rear fenders being a mirror image thereof;

FIG. 2 is an upper perspective view thereof;

FIG. 3 is an side view thereof;

FIG. 4 is a front view thereof;

FIG. 5 is a rear view thereof;

FIG. 6 is a top view thereof; and,

FIG. 7 is a bottom view thereof.

The other one of the pair of rear fenders not shown is a mirror image of FIGS. 1 through 7. The broken lines shown in the drawings illustrate environmental subject matter which forms no part of the design.
